UNITED STATES PATENT OFFICE.

SAMUEL STEINECKE, OF BROOKLYN, NEW YORK, ASSIGNOR TO CHRISTIAN A. SCHMIDT, OF HOBOKEN, NEW JERSEY.

DESIGN FOR GIMP.

SPECIFICATION forming part of Design No. 18,173, dated March 6, 1888.

Application filed January 9, 1886. Serial No. 260,243. Term of patent 14 years.

To all whom it may concern:

Be it known that I, SAMUEL STEINECKE, of Brooklyn, county of Kings, State of New York, have invented a certain new Design for Gimp, 5 of which the following is a specification.

In the accompanying drawing a face view of my newly designed gimp is shown.

The leading feature of my design consists of three longitudinal rows of lenticular projections and stripes above and below the rows of lenticular projections, the stripes being composed of short lines separated by interstices.

A represents the top and bottom headings of the gimp. B represents lenticular projections forming the three longitudinal rows C', C², and C³, occupying the central longitudinal part of the body of the gimp. The lenticular projections B of the rows C' and C³ are inclined in the same direction and the lenticular projections B 15 of the row C² in the opposite direction, and the lenticular projections of the three rows have their joints alternating. D D' are longitudinal stripes above and below the group of the three longitudinal rows C' C² C³ of lenticular projec-

tions B, each stripe D and D' being composed 25 of three rows of a series of short lines, d, separated from each other at the ends by interstices of uniform size, the interstices of the three rows of lines in each stripe alternating regularly.

Having thus described my design, I claim as new and desire to secure by Letters Patent—

The design for gimp, consisting of longitudinal rows of lenticular projections, and stripes above and below the groups of rows of lenticular 35 projections, said stripes being composed of rows of short lines separated by interstices, the interstices in the several rows of each stripe alternating, substantially as herein shown and described.

In testimony that I claim the foregoing as my invention I have signed my name in presence of two subscribing witnesses.

SAMUEL STEINECKE.
